(57) **CLAIM**

The ornamental design for a hair brush, as shown and described.

DESCRIPTION

FIG. 1 is a bottom, front perspective view of an ornamental design for a hair brush according to the present invention; FIG. 2 is top, front perspective view of the hair brush of FIG. 1;

FIG. 3 is a front elevational view of the hair brush of FIG.1; FIG. 4 is a rear elevational view of the hair brush of FIG. 1; FIG. 5 is a left elevational view of the hair brush of FIG.1; FIG. 6 is a right elevational view of the hair brush of FIG.1; FIG. 7 is a top plan view of the hair brush of FIG. 1; and, FIG. 8 is a bottom plan view of the hair brush of FIG. 1. The broken line showing of FIGS. 1-8 is for the purpose of illustrating environmental structure and forms no part of the claimed design.
